UNITED STATES PATENT OFFICE.

FREDERICK PEITER, OF CLEVELAND, OHIO.

COKE-OVEN.

1,267,332.

Specification of Letters Patent. Patented May 21, 1913.

Application filed September 11, 1913. Serial No. 112,352.

To all whom it may concern:

Be it known that I, FREDERICK PEITER, a citizen of the United States, residing at Cleveland, in the county of Cuyahoga and State of Ohio, have invented a certain new and useful Improvement in Coke-Ovens, of which the following is a full, clear, and exact description, reference being had to the accompanying drawings.

10 This invention relates generally to coke ovens of the by-product type, and comprehends a novel form of combustion flue construction by means of which uniformity of heating of the ovens is attained.

15 An object of the invention is to provide an oven in which it is possible to maintain a flame of practically the same length as the combustion flue, and which produces and distributes the heat substantially uniformly 20 throughout the length of the flue. It is a further object of the invention to so control the combustion as to prevent the maximum combustion temperature from reaching the fusion temperature of the oven structure and to maintain the flues at practically 25 this combustion temperature for their entire lengths to the end that the coking is accomplished at a uniformly high rate of speed over the entire area of the oven and that a 30 better and more uniform grade of coke is produced in a shorter time than heretofore.

With these broad objects in view and with certain other objects which will become apparent as the description proceeds the invention 35 consists in the novel form of construction hereinafter fully described and pointed out in the claims.

In order to more readily understand the merits of the invention the following observations are made concerning the present 40 status of the coke making art.

It has been the practice to use combustion flues of a considerable length introducing gas and highly preheated air at one end 45 thereof in the proper proportions to produce complete combustion, and allowing the products of combustion to pass out through a checkerwork connected to the opposite end. This operation is reverse, at intervals, the 50 gas and air being introduced during each operation through the checkerwork heated by the escaping products of combustion of the immediately previous operation. The maximum temperature of combustion under 55 these conditions is higher than the safe temperature of the refractories of which the

oven flues are constructed. This practice has accordingly resulted in such a high temperature in a zone near the burner as to fuse the brick if not very carefully regulated; a lower temperature near the center of the flue; and a much lower temperature near the opposite end. This is not an efficient method of operation for the reason that while the temperature near the burners 60 is dangerously high, the temperature of the balance of the flue is much lower than it should be. It is evident that much better results would be secured if the temperature of the flue near the burner were reduced to 70 a temperature below the fusion point of the fire brick, the length of the flame increased, and the temperature of the balance of the flue made higher. It is obvious that, under such conditions, the danger to the oven structure would be practically eliminated; the 75 coal would be coked more uniformly; and the rate of coking increased.

In the accompanying drawings forming a part of this specification I have shown one 80 form of coke oven for carrying out my invention. In the drawings Figure 1 is a top plan view of one-half of the coke oven, the other half being broken away as indicated by the line 1—1 of Fig. 3; Fig. 2 is a section on the staggered line 2—2 of Fig. 1; and Fig. 3 is a section on the staggered line 3—3 of Fig. 1.

Referring to the drawings, 5—5 indicate a series of vertical flues which have communication with the regenerators 10, which are of any approved construction, and between these vertical flues are arranged the combustion flues 1, 2, 3, and 4, in groups of four as shown, each vertical flue 5, serving 85 alternately as an inlet to receive the preheated air from the regenerator and then as an outlet or passageway through which the burned gases pass to the regenerator. The preheated air passes up through each alternate flue 5, and on reaching the top divides, one half going into each of the two adjacent groups of flues. The air passes in a horizontal direction, as indicated at 6, into the top of the first of the four combustion 90 flues of each of the adjacent series which, in the drawing, is designated 1, and where approximately one half enough combustible gas to satisfy the passing air is introduced through the primary burner 7. The air and 95 gas pass down through the first flue 1, combustion taking place during the passage 100 of the air through the flue 1, the products of 105 combustion passing through the flue 1 to the second flue 2, and so on through the remaining flues 110 2, 3, and 4.

down the flue and up through flue 2. On account of the excess of air, the temperature produced by the combustion is lower than it would be if the air and gas were mixed 5 in the proper ratio for complete combustion. As it is desirable to burn all of the gas introduced by burner 7 before it reaches the top of flue 2, the bottoms of the flues 1 and 2, where they unite, are shaped to produce eddies as indicated at 8, and a baffle 9 is arranged about midway the height of each flue 2. The thorough mixing of the gas and air by these eddies accelerates the combustion and production of heat at 10 these points and insures the complete combustion of the gas from burner 7 before it arrives at the top of flue 2.

From flue 2 the burned gas and the extra supply of air pass horizontally, as indicated 20 at 11, into the top of flue 3, where an additional amount of gas is introduced through the burner 12, this additional gas being introduced in a sufficient quantity to completely combine with and satisfy the free air 25 present at that point with the result that a second combustion occurs. This second combustion takes place down flue 3 and up flue 4, but in flue 3 there is also preferably arranged a baffle 9, at the proper point, for 30 the purpose of accelerating the combustion so that by the time the gases have passed baffle 9, and have been further mixed in their passage from flue 3 to flue 4 the combustion will be complete on arrival of the 35 gases at the top of flue 4. From flue 4 of each series, the burned gases pass out through the horizontal passageway 6 communicating with the adjacent vertical flue 5, which, in the present operation, carries the products 40 of combustion to the regenerator; and which, upon a reversal of the operation, acts to conduct preheated air from the regenerator into the series of combustion flues.

The temperature which a gas can produce 45 in burning depends upon the heat value of the gas, the specific heat of the gas mixture in which it is burned, the mass of this mixture and the rate at which the heat is taken away from this mixture by the walls of the 50 combustion chamber. The introduction of the excess of air at the primary burner and the presence of the waste gases from the first combustion at the secondary burner therefore reduce and accurately control the temperature 55 at these points thereby preventing overheating and at the same time permitting a temperature high enough for satisfactory coking.

A careful consideration of the dynamics 60 of the combustion of gas will serve to make clear the cause of the even heating which results from this arrangement. Since the air is preheated to beyond the kindling point of the combustible gas, as soon as a molecule 65 of this gas comes in contact with a molecule

of the oxygen combustion takes place. The rate of combustion will therefore depend upon the rate of the mixing of the active gases. In other words it will follow the well known law of mass action. This is true 70 when the air and gas enter the chamber at the same lineal velocity and any relative change in the velocity of either will hasten this rate as will also anything causing a swirl, such as a baffle or change of direction. 75

The law of mass action is logarithmic, *i. e.* the rate of burning is slower as the burning gas gets farther from the burner, the rate changing in a logarithmic curve. It is evident therefore that under the old method the 80 combustion is at first intense and then rapidly weakens. By my method, the temperature near the first burner is controlled by the excess of air and near the second burner by a dilution with the products of combustion 85 from the first combustion. The flame length is greater in the last case as a direct result of this dilution and in both cases the temperature curve is made much flatter on account of the much greater amount of the gas 90 mixture and its high rate of travel, and by the two flames combined I am able to maintain a much more uniform temperature throughout the entire length of the flue and a temperature at the points of greatest intensity 95 below the temperature of the fusion of the flue walls. Since the flue walls receive by far the greater part of their heat by radiation from the incandescent gas mixture, it is important to note that the rate at 100 which two hot bodies exchange heat by radiation is proportional to the fourth powers of their absolute temperatures. From which it is evident that, while some loss is experienced due to the reduction of temperature 105 at the maximum points, this is necessary for the safety of the structure and this loss is far more than regained by the distribution of the high temperature over a greater proportion of the total length of the flue. 110

Having thus described my invention, what I claim is:—

1. In a coke oven, combustion flues arranged in groups of four and in serpentine order, a flue having communication with a 115 regenerator and adapted to convey preheated air to the combustion flues, means for supplying combustible gases at corresponding portions of the first and third flues, and a flue communicating with the fourth flue of 120 each group and leading to a regenerator.

2. In a coke oven, combustion flues arranged in groups of four in serpentine order, a flue communicating with each group of 125 four and adapted to supply preheated air thereto, means for supplying combustible gas to each group at spaced points and baffles arranged in the second and third flue of each group, and flues communicating with each group and leading to a regenerator. 130

3. In a coke oven, combustion flues arranged in groups of four and in serpentine order, a flue having communication with a regenerator and adapted to convey preheated air to the combustion flues, means for supplying combustible gases at the top of the first and third flues and a flue communicating with the fourth flue of each group and leading to a regenerator.
4. In a coke oven, combustion flues arranged in groups of four, in serpentine order, a flue communicating with a regenerator, and adapted to deliver preheated air to the first flue of each group, means for introducing combustible gases at the top of each first flue, a baffle in the second flue of each group, means for introducing gas at the top of the third flue of each group, and a baffle located in said third flue and a flue communicating with the fourth flue of each group and leading to a regenerator.

In testimony whereof I hereunto affix my signature.

FREDERICK PEITER.
